UNITED STATES PATENT OFFICE

ARTHUR B. MODINE, OF RACINE, WISCONSIN, ASSIGNOR TO MODINE MANUFACTURING COMPANY, OF RACINE, WISCONSIN, A CORPORATION OF WISCONSIN

CONCEALED RADIATOR

Application filed May 15, 1929. Serial No. 363,916.

My invention relates to household heating apparatus and particularly to household heating apparatus which may be installed in the walls of houses or other buildings.

5 The invention has among its other objects the production of apparatus of the kind described, which is compact, convenient, durable, efficient and which may be installed in buildings already in existence.

10 A further object of the invention is the provision of improved apparatus of the kind described which is readily accessible for repairs and which is easily dismantled and removed for renewal or repairs.

15 Another object of the invention is the provision of apparatus of the kind described, which may be readily installed in a relatively narrow wall.

Still another object of the invention is the 20 provision of apparatus of the kind described, which may be removed from its mounting without tearing out any portion of the wall in which it is positioned.

25 Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

In the drawing, wherein like reference characters indicate like or corresponding 35 parts:

Fig. 1 is a fragmentary elevational view of a wall in which apparatus embodying the invention is installed;

Fig. 2 is a section along the line 2—2 of 40 Fig. 1; and

Fig. 3 is a section along the line 3—3 of Fig. 2.

Referring to the drawing wherein I have shown a preferred form of the invention embodied in apparatus which is installed in a wall or partition forming part of a dwelling or other building, the wall being generally designated by the numeral 10, is of any type commonly employed in dwellings and other 45 buildings of a similar character.

The wall 10 is shown as comprising studding 11, spaced apart to permit a duct 12 to be positioned therebetween. The studding may be covered by any suitable material such as plaster, plaster board, or the equivalent, 55 as indicated at 13. Upper and lower apertures 14 and 15, respectively, being formed in the wall 10 to provide discharge outlet and inlet openings, respectively. The duct 12 has vertically extending end walls 16 connected by front and rear walls 17 and 18, respectively.

The rear wall 18 has its upper portion turned outwardly with its end terminating in alignment with the surface of the wall 13. 65 The upper end of the front wall section 17 is also turned outwardly terminating in the face of the plaster wall 13, the horizontal portions of the walls 17 and 18 together forming the upper and lower boundaries of the 70 aperture 14. The lower end of the front wall section 17 terminates at the upper edge of the aperture 15. The lower end of the rear wall section 18 terminates at considerable distance below the corresponding terminus of the 75 front wall section 17. If desired, the rear wall section 18 will extend to the floor.

A radiator unit 20 is positioned in the duct 12 preferably immediately above the aperture 15. The radiator unit 20 comprises 80 a plurality of horizontally extending tubes 21 which connect header tanks 22 oppositely positioned in the duct 12. The tubes 21 are of relatively narrow construction and are placed side by side to form a thin radiator 85 unit, the number of tubes being varied to suit the thickness of the wall in which the duct 12 is positioned. A plurality of transversely extending fins 23 are mounted on the tubes 22 to accelerate the transfer of heat 90 from the radiator unit 20 to the column of air ascending through the duct 12.

The radiator unit 20 is supplied with heating fluid through a main pipe 26. The flow of heating fluid to the radiator unit is controlled by a valve 27 which is connected with a union 28 by means of a nipple 29. A nipple 30 connects the union with an L 31. A vertically extending pipe section 32 connects the L 31 with the radiator unit 10. The valve 100

27 and the union 28 are positioned adjacent the lower aperture 15 for convenience in controlling the heat and dismantling the device.

The length of the pipe 32 may be varied to 5 suit the requirements of the installation, such length being dependent upon the height of the lower aperture 15 and the distance the radiator unit is positioned above the aperture. The radiator unit 20 is connected with 10 a discharge pipe 38 through the medium of a vertically extending pipe 33. The pipe 33 is positioned opposite to the pipe 32 and preferably of the same length. A horizontal pipe 35 is connected with the pipe 33 by 15 an L 34 and with the discharge pipe 38 through a union 36 and a steam trap 37. The various L's and unions connecting the main feed pipe 26 and discharge pipe 38 with the radiator unit 20 are positioned adjacent the 20 lower aperture 15 so as to be accessible for detachment for repairs or in case it is found desirable to remove or replace the radiator unit 20. The radiator unit 20 can be removed by merely unthreading the pipes 32 25 and 33 from the L's 31 and 34, respectively, the pipes being preferably of the same length and for this purpose similarly arranged.

A grille 24 partially closes the upper aperture 14. A grille 25 similarly closes the 30 lower aperture 15. The grille 25 is provided with a hinged connection 26' by means of which the grille may be opened to permit access to the heating device when desired.

Thus it will be seen that I have provided a 35 heat exchange unit adapted to be easily installed in, and removed from, relatively narrow walls, either old or new, and which is so constructed as to be easily accessible for inspection and for repairs.

40 Having thus described my invention, it is obvious that various immaterial modifications may be made in the same without departing from the spirit of my invention; hence, I do not wish to be understood as limiting myself to the exact form, construction, arrangement and combination of parts herein shown and described, or uses mentioned.

I claim:

1. In a device of the class described, the 50 combination of a vertically extending casing and a horizontally extending radiator arranged in the lower portion of the casing above the lower edge of the front wall of said casing, fluid conducting pipes located in the 55 casing, the lower edge of the front wall of the casing being located above the lower edge of the rear wall to thereby provide an opening in the front wall of the casing, said opening providing means through which said radiator 60 may be passed and said pipes being arranged to allow said radiator to be passed over said pipes to introduce and remove said radiator from within the interior of said casing and into and out of cooperative relation with said 65 pipes.

2. In a device of the class described, the combination of a vertically extending casing and a horizontally extending radiator arranged in the lower portion of the casing above the lower edge of the front wall of said 70 casing, the lower edge of the front wall of the casing being located above the lower edge of the rear wall to thereby provide an opening in the front wall of the casing, said opening providing means through which said 75 radiator may be passed to introduce and remove said radiator from within the interior of said casing, fluid supply and return pipes, and connections providing means for connecting said radiator with said fluid supply 80 and return pipes, said connections and an element of said supply and return pipes being located entirely within the space below said radiator, and said radiator being movable 85 across an end of said pipes into and out of functional relation with said supply and return pipes.

3. In a device of the class described, the combination of a vertically extending casing and a horizontally extending radiator arranged in the lower portion of the casing adjacent the lower edge of the front wall of said casing, the lower edge of the front wall of the casing being located above the lower edge of the rear wall to thereby provide an 90 opening in the front wall of the casing, said opening providing means through which said radiator may be passed to introduce and remove said radiator from within the interior of said casing, tubular means extending from 95 said radiator arranged below said radiator, fluid supply and return pipes located in said casing, said tubular means of said radiator providing means connecting said radiator with said fluid supply and return pipes and 100 including a connection providing means for separably attaching said radiator with said fluid supply and return pipes, said pipes being arranged to allow said radiator to be moved across an end of said pipes into and 105 out of said casing and into and out of functional engagement with said pipes.

4. In a device of the class described, the combination of a vertically extending casing and a horizontally arranged radiator arranged in the lower portion of the casing adjacent the lower edge of the front wall of the casing, fluid supply and return pipes in said casing, said edge of said casing being located in spaced relation to the floor of the room in which said casing is located to thereby provide an opening in the front wall of the casing, said opening providing means through which the radiator may be passed to introduce and remove said radiator from within said casing and said pipes being arranged to allow the radiator to be passed over an end of said pipes into and out of functional engagement with said pipes.

5. In a device of the kind described, the 130

combination of a vertically extending casing and a horizontally arranged radiator located in the lower portion of the casing, the lower edge of the front wall of the casing being spaced from the floor of the room in which said casing is located and providing an opening through which the radiator may be introduced and removed from said casing, fluid supply and return pipes, fittings providing means for connecting said radiator with said fluid supply and return pipes, said pipes terminating in vertical spaced relation to the lower edge of the front wall, to thereby provide a space between said edge and said terminations in which said radiator is removably located.

6. In a device of the kind described, the combination of a casing, a radiator and fluid conducting pipes for circulating fluid to and from said radiator, said casing being open at its lower end to provide means through which air may be introduced to said casing and said radiator may be removably introduced to said casing, said pipes being arranged in said casing with their ends terminating in spaced relation to the upper termination of said opening, said radiator having tubular extensions adapted for connection with said pipes, and means for separably connecting said extensions with said pipes, said radiator being movable in horizontal and vertical directions relatively to said pipes to effect association and removal of said radiator and said casing and said pipes.

35. 7. In a device of the class described, the combination of a vertically extending casing and a horizontally extending radiator arranged in the lower portion of the casing adjacent the lower edge of the front wall of said casing, said edge of said casing being arranged in spaced relation to the floor of a room in which said casing is located to thereby provide an opening at the front wall of the casing, said opening providing means through which said radiator may be passed to introduce and remove said radiator from within the interior of said casing, fluid supply and return pipes located in said casing, fittings providing means for detachably connecting the radiator with said fluid supply and return pipes, said fittings and fluid supply and return pipes providing a support for the radiator unit, and said supply and return pipes terminating in vertical spaced relation to an edge of said opening to thereby provide a space between said edge and terminations into which said radiator is introduced to arrange radiator adjacent said edge of the opening.

60. In testimony whereof, I have hereunto signed my name.

ARTHUR B. MODINE.
